UNITED STATES PATENT OFFICE.

SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

VAPOR-RECTIFIER.

1,244,483.

Specification of Letters Patent. Patented Oct. 30, 1917.

Application filed April 6, 1914. Serial No. 829,825.

To all whom it may concern:

Be it known that I, SIDNEY W. FARNSWORTH, a citizen of the United States, and a resident of Pittsburgh, in the county of Allegheny and State of Pennsylvania, have invented a new and useful Improvement in Vapor-Rectifiers, of which the following is a specification.

My invention relates to vapor apparatus 10 and more particularly to liquid electrodes therefor.

The object of my invention is to construct a liquid electrode of the character specified which will be but slightly affected by violent mechanical agitation and which will readily dissipate heat.

In the accompanying drawing, Figure 1 is a view, in section, of my invention and Fig. 2 is a plan view of the same. Figs. 3 and 5 20 are plan views of modifications, and Figs. 4 and 6 are views, in section, of the structures shown in Figs. 3 and 5, respectively.

A containing receptacle 1 of any suitable material, such, for example, as steel, is provided with an anode 2, insulated therefrom, as shown at 3, and with a liquid cathode 4 of any suitable material, such for example, as mercury. In the operation of devices of this character, as is well known in the art, 30 a rectifying arc flows between the anode and the cathode, being confined to the central portion of the latter by means of a refractory insulating ring 5. Rectifiers of this type are frequently mounted upon electric locomotives or similar moving vehicles wherein the mercury of the cathode is subjected to violent agitation, with consequent disturbance and instability of the arc. In order to eliminate this defect, I submerge 40 a plate 6 of some refractory material, such, for example, as steel, in the liquid of the cathode. Steel is especially suited for this purpose because it does not amalgamate or otherwise combine with the substances ordinarily employed for liquid electrodes. Furthermore, steel being a comparatively good conductor of heat, will transmit to the wall of the container a large amount of the heat that is generated at the surface of the cathode.

50 The plate 6 may be fastened to the bottom of the container by any suitable means, such, for example, as bolts 9 engaging threaded lugs 10 that are welded to the container. The upper surface of the plate 6 55 is provided with a number of intersecting

grooves 7 as clearly shown in Fig. 2 and, from the bottom of these grooves, a number of openings 8 extend to the lower surface of the plate. In the operation of the device, a large portion of the cathode metal will 60 rest in these grooves and the cohesion between this portion and the liquid overlying the plate will greatly retard the free movement of the latter. During rapid acceleration or violent breaking of the vehicle, the 65 cathode material of a large portion of the cathode may be momentarily carried to one side of the container but I find that a sufficient amount will remain in the grooves 7 to insure a steady arc. The openings 8 insure a free path of escape for mercury that may find its way beneath the plate, allowing it to rise to the active portion of the electrode.

I am aware of British Patent 22,246 of 75 1912 wherein is disclosed a somewhat similar structure but the upper surface of the grooved plates in this foreign patent intentionally projects above the liquid of the electrode, the purpose being to distribute the 80 arc and cause a more uniform heating of the electrode. The grooved plate in my device is never intended to be exposed except under abnormal conditions. It is not necessary to provide any special means for enlarging the active portion of the cathode 85 since I find that, with the amount of current ordinarily employed in a device of the character indicated, the arc will extend to the entire surface of the cathode inclosed 90 by the ring 5.

Referring to the form of my invention shown in Figs. 3 and 4, I find that the liquid of the cathode may be effectually restrained from violent splashing by mounting a plurality of members 12 directly on the bottom of the container. These may be short pieces of rod or pipe and may be attached to the container in any suitable manner, such, for example, as by welding. I 100 consider the pipe particularly effective since it forms a plurality of small cups, each of which restrains a certain amount of the cathode liquid.

In the form of device shown in Figs. 5 105 and 6, a ring member 13 is attached to the bottom of the container, in a similar manner to the member 6 in Fig. 1, and is provided with an interior flange or seat 14. Resting on the seat 14 is a grid 15 of any 110

suitable material, such, for example, as steel, which retards the free movement of the cathode material.

Obviously, my invention may be modified in various ways without departing from the spirit thereof and, therefore, I do not desire to be restricted to the specific forms illustrated but intend that my invention shall cover, in general, all means for mechanically restraining and preventing free motion of the electrode material with respect to the container.

Having thus described my invention, what I claim is:

- 15 1. In vapor electric apparatus, the combination with a liquid electrode, of a member submerged slightly below the surface thereof and having a plurality of depressions in its upper surface, said member being substantially coextensive with the active portion of said electrode.
- 20 2. In vapor electric apparatus, the combination with a liquid electrode, of a member submerged slightly below the surface thereof and having a plurality of grooves in its upper face, said member being substantially coextensive with the active portion of said electrode.
- 25 3. In vapor electric apparatus, the combination with a liquid electrode, of a member submerged slightly below the surface thereof and having a plurality of intersecting grooves in its upper face.

4. In vapor electric apparatus, the combination with a liquid electrode, of a member submerged therein and having a plurality of intersecting grooves in its upper face and a plurality of openings extending through said member from the bottom of said grooves to the lower face of the member.

5. In a vapor rectifier comprising a containing receptacle and suitable electrodes therein, the combination with a liquid electrode, of a member submerged slightly below the surface thereof and attached to the bottom of the receptacle and provided with a plurality of grooves in the upper face thereof.

6. In a vapor rectifier comprising a containing receptacle and suitable electrodes therein, the combination with a liquid electrode, of a metallic plate submerged therein and attached to the bottom of the receptacle and provided with a plurality of intersecting grooves in its upper face and having openings extending from the bottoms of some of said grooves to its lower face.

In testimony whereof, I have hereunto subscribed my name this 31st day of March, 1914.

SIDNEY W. FARNSWORTH.
